UNITED STATES PATENT OFFICE

JAMES H. BONNET, OF CHAMPAIGN, ILLINOIS

FABRIC CANOPY SUPPORT

Application filed August 14, 1931. Serial No. 557,143.

This invention relates to improvements in fabric canopy supports; and consists in the novel construction hereinafter disclosed.

In a copending application Serial No. 557-5 142, filed Aug. 14, 1931, there is disclosed and described a knock-down portable bench, and in said application the invention is directed to the mechanical construction of the bench with the overhanging support. This invention is confined to the details of construction 10 of the support with the method of attaching thereto the elements of the covering.

An object of the invention, therefore, is to provide an improved fabric canopy support 15 which may be readily assembled and disassembled, with convenient means for attaching thereto a fabric roof member and a drop member.

Additional advantages of the construction 20 will be apparent from the following detailed description thereof taken in connection with the accompanying drawing, in which—

Fig. 1 is a vertical section through the construction.

Fig. 2 is a fragmentary detail view in plan of the front and back connecting means for connecting the roof fabric to the supporting arms.

Fig. 3 is a section illustrating the construction 30 of the front connecting means for connecting the roof fabric in place.

Fig. 4 is a view of the rear of the supporting arms with the connecting means shown therewith.

Fig. 5 is a cross-section on the line 5—5 of Fig. 1.

From the copending application above referred to, it will be understood that the complete bench is composed of a number of units, 40 each unit comprising a support, a bench member on the support, a vertical standard having a removable arm, the several arms forming a roof support. It is unnecessary, therefore, to duplicate the units, it being under-

stood that they are assembled as shown in the copending application.

With special reference to the construction disclosed in the drawing of the present case, 1 indicates the collapsible support unit, 2 the section of the bench supported by the unit, and 3 the standard held in vertical position by the support, said standard being connected to the support by sockets 4. The standard 3 is given rigidity in a lateral direction by one 50 or more brace members 5 connected to the support at one end and to a spike construction 5 at the other end, it being understood that the spike is driven into the ground to support the standard. The standard 3 carries at its 60 upper end an arm 7. The arm 7 is formed with a tubular socket 8, a bracing web 9 extending forwardly from the socket and a web 10 extending rearwardly from the socket. The arm 7 is preferably formed from a tubular 65 piece of pipe having the rear extremity flattened at 11 and the forward end flattened at 12. A lever 13 that is U-shaped in cross-section is pivoted to the extremity of the web 10 at 14. A U-shaped bail 15 has its arms pivoted at 16 to the lever 13 and has its upper end turned over to form a curved portion 17. There is a similar connecting construction 70 at the forward end of the arm 7 and, since the parts correspond substantially in function 75 and in construction, similar reference numerals have been applied thereto.

The roof fabric 18 comprises a longitudinal strip of cloth that is stretched across the several arms 7 of the completed construction 80 and is held in place in connection with the arms 7 releasably. In order to connect the roof section with the arms, the roof section is provided with a series of rods 19 that are mounted longitudinally of the front and rear 85 edges of the roof section. The rods 19 have downturned extremities 20 that fit into openings in the flattened faces of the members 11 and 12, respectively. The rods are held in place in said openings by engaging the curved 90

sections of the bails 15 over the top face of the rods 19 adjacent to the downturned extremities, and the levers 13 operated to lock or latch the rods in position. In order to facilitate the adjustment of the latch construction, the roof section is cut out at 21 adjacent to the extremity of the rods 19.

In order to support the rear drop 22 of the canopy covering, along the rear longitudinal edge of the roof section there is provided a series of eyes 23 with cooperating snaps 24 supported along the upper margin of the drop. In order to hold the drop in place, the drop is provided with spaced connecting means in the form of strip snaps 25, thus holding the lower section of the rear drop vertically against the back of the bench construction.

I am aware that the invention may be modified in numerous particulars without departure from the spirit and scope thereof, but what I claim and desire to secure by Letters Patent is:—

1. In a construction of the class described, the combination of a standard, a support for said standard, a removable arm carried by the upper end of said standard, said arm having a pair of openings in each end thereof, a roof section supported by the arm, a longitudinal series of rods enclosed in the roof section and having downturned extremities seating in said openings, and a releasable latch device carried at the front and rear ends of said arm for clamping said rods to hold said extremities in said openings.

2. In a construction of the class described, the combination of a standard, an arm supported thereby, a roof section comprising a rectangular sheet of fabric, a series of rods enclosed in the roof section along the front and rear marginal edges thereof and adapted to connect at the front and rear ends of said arm, and a releasable clamp device for holding said rods in connection with said arm.

3. In a construction of the class described, an arm constituting a roof support, a pivoted lever at each end of said arm, a bail connected with each of said levers, said bails having an overturned upper portion, and a flexible roof section having a plurality of rods supported by the flexible roof section along the front and rear margins thereof and adapted to be releasably held in place by said bails when the levers are in locked adjustment.

4. In a construction of the class described, an arm constituting a roof support, webs at each end of said arm, a lever pivoted to said webs and adapted to be moved to a latched and unlatched position, a bail connected with each of said levers, said bails having an overturned upper portion, and a flexible roof section having a plurality of rods supported by the flexible roof section along the front and rear margins thereof and adapted to be

releasably held in place by said bails when the levers are in locked adjustment.

5. A fabric canopy support comprising in combination a standard, an arm removably supported by the standard, a roof section comprising a flexible wall, a series of rods enclosed in the roof section along the front and rear marginal edges thereof and adapted to be connected at the front and rear edges thereof to said arm, and releasable clamp devices for connecting the rods with said arm.
